SOLE PRESS OF THE TURRET TYPE

Harold E. Marasco, Swampscott, Mass.

Application April 4, 1951, Serial No. 219,215

11 Claims. (Cl. 12—36.8)

1

This invention relates to sole pressing machines of the turret type and particularly, though not exclusively, to presses for conforming and attaching outsoles to bottoms of lasted shoes.

Sole laying machines are used for pressing a sole against the bottom of a shoe in order to cause the sole to conform closely to the curves of the shoe bottom. In using a sole laying machine in making cemented, welted or McKay sewed shoes, an adhesive is present and the pressing not only shapes the sole but it attaches it in place in the shoe bottom.

Objects of this invention are to provide an improved and simplified machine for work of the general nature indicated in the operation of which the operator will not have to wait for the machine to function but can work to his full capacity, and to provide a machine in which the work is presented to the operator in the most convenient position for inspection of the work, and in which the work may be clamped in the machine under pressure by a minimum manipulation of parts.

To these ends, the machine of my invention comprises a number of pressing units radially disposed in a turret which is movable to present the units progressively in work-receiving and work-discharging position, and fluid pressure applying means operating while each unit is in convenient angular position and independent of movement of the turret for applying pressure to that unit and relieving pressure simultaneously in respect to another unit of the series.

In the illustrated machine, each pressing unit comprises a shoe holding device and an inflatable sole engaging pad adapted to apply pressure to the shoe bottom while the pad is in shoe receiving position. The shoe engaging pads are herein shown as arranged for rotation with the turret in a horizontal plane and are inclined downwardly and outwardly with respect to the axis of the turret to facilitate inspection of the shoe and the sole placed thereon and while these parts are under pressure.

Going more into detail, the machine herein shown comprises a vertical cylinder rotatably mounted in the frame of the machine, having an inlet connection and acting as a fluid pressure reservoir. The inflatable pads are carried by this cylinder in radial relation and each has a fluid pressure connection with the cylinder. As herein shown the cylinder is utilized as a carrier for both the upper and lower pressing elements, this double function of the cylinder contributing largely to the simplification and compactness of my novel machine.

Another important feature of the machine

2

consists in a supporting member mounted on the cylinder for vertical adjustment and carrying the upper of said pressing elements together with means under the control of the operator for adjusting the supporting member and the pressing elements carried thereby.

Other features of the invention relate to the fluid pressure system which includes a swivel inlet connection to the rotatable cylinder, to means for automatically controlling the valves of the fluid pressure system, and to novel means for controlling the power operation of the machine. Novel and convenient mechanism for adjusting the inflatable pads while maintaining their fluid pressure connections undisturbed will also be described, together with other features of the machine which will be best understood and appreciated from the following description of a preferred embodiment thereof, selected for purposes of illustration and shown in the accompanying drawings in which:

Fig. 1 is a plan view of the machine.

Fig. 2 is a view in cross-section on the line 2—2 of Fig. 5.

Fig. 3 is a fragmentary detail of one of the inflatable pads and associated parts.

Fig. 4 is a view in cross-section on the line 4—4 of Fig. 5.

Fig. 5 is a partial view in elevation showing portions of the frame broken away.

Fig. 6 is a view in longitudinal section on the line 6—6 of Fig. 1.

Fig. 7 is a fragmentary view of the frame at right angles to that shown in Fig. 5.

Fig. 8 is a fragmentary view in perspective as seen from the line 8—8 of Fig. 1, and

Fig. 9 is a view in longitudinal section of the valve in the pressure line between the cylinder 14 and each of the inflatable pads.

The illustrated machine comprises a cylindrical frame or supporting column 10 having a bottom 11 and a top 12 all secured rigidly together by three tubular tie rods 13. Rotatably mounted in the top 12 is a vertically disposed cylinder 14 supported on ball bearings 15 by a circumferential flange. The cylinder 14 serves as a carrier for the pressing elements of the machine and also as a reservoir for compressed air or other fluid. To this end, it is sealed at its lower end by a disk 16 and to this is bolted a driven disk 17 of a Geneva motion. The disk 17 has six lobes and these correspond to the pressing elements carried by the cylinder 14 as will presently appear. The disk 17 is driven intermittently by a mutilated disk 18 pinned fast to the upper end

55 of a vertical shaft 19. The shaft 19 is provided near its lower end with

a bevel gear 20 meshing with a bevel gear 21 on the right hand end of a horizontal shaft 22, best shown in Fig. 5 as journaled in bearings projecting upwardly from the bottom 11 of the machine frame. The shaft 22 carries a sprocket wheel 23 which is driven at a constant speed by a motor 24 bolted to the bottom 11 of the frame. Between the sprocket wheel 23 and the bevel gear 21 is interposed a one-revolution clutch 25. This is arranged to be tripped by a dog 26 pivotally mounted on a rod 27 supported by upstanding lugs on the bottom 11 and shown in Fig. 7 as connected through a link 28 to an operating handle 29 pivotally mounted in bearings beneath the top 12 of the machine frame. It will be understood that when the operating handle 29 is depressed by the operator, the clutch is released and a single revolution imparted to the shaft 22. This, in turn, operates through the Geneva motion and indexes the cylinder 14 of the turret through 60°.

The illustrated machine is shown as provided with six work pressing units, although it may be desired to include any convenient number. The cylinder 14 is provided with six outwardly extending radially disposed arms 31 in the form of vertical plates each carrying at its outer edge a flat base plate 32 disposed at an angle of approximately 45° to the horizontal. Each base plate is provided with a central longitudinal slot 33, as shown in Fig. 8, and serves as a support and guide for a rectangular box 34. Each box has a downwardly extending lug at its lower outer edge through which passes an adjusting screw threaded into a corresponding lug on the bottom of the base plate 32. Each box has hooked lugs at its side edges which extend over the bottom of the base plate 32 so that the latter acts as a guide and permits longitudinal adjustment of the box 34 thereon. Each of the boxes is provided with flanged side walls and these enclose an inflatable pad 36 of rubber, leather or flexible composition which is adapted to shape itself automatically to the bottom of the lasted shoe and conform the outsole thereto when inflated. A flexible hose 37 extends through the slot 33 in the base plate 32 and makes a pressure connection through the bottom of the base 34 with the inflatable pad 36. Each hose 37 is connected to the outer end of a pipe 38 which extends radially from the cylinder 14. In each of the pipes 38 is included a controlling valve operated by a sliding sleeve 40. The sleeve is shifted to open or close the valve by a cam arm 41 having a roller 42 at its inner end and being pivotally mounted in a bracket 39 depending from each of the pipes 38. The valve operating arm 41 is shifted to and held in its open position by the action of a circular cam 43 fast on the top 12 of the machine frame in proper position to engage the roller 42 of the arm. An angular abutment 44 is arranged to engage the top of the bracket 39 to guide and support the outboard portion of each of the pipes 38 in their rotary movement with the cylinder 14. The valve arm 41 may be operated manually at any time to close the valve, or it may be operated in the final station of the machine by a vertical rod 45 located within the cylindrical frame 10 and connected at its lower end to a treadle 46. A fluid pressure supply pipe 47 passes through the Geneva disk 17 and is threaded into the bottom 16 of the cylinder 14. It is connected through a swivel joint 48 to any convenient source of fluid pressure as, for example, to an air compressor. Through this inlet connection full fluid

pressure is maintained at all times within the chamber of the cylinder 14.

The upper end of the cylinder 14 is closed by a head 50. A sleeve 51 is telescopically mounted upon the upper end of the cylinder 14 and together with a disk 52 forms a head or the hub of a spider vertically adjustable by means of a hand wheel 53 having a stem threaded into the head 50 of the cylinder. The sleeve 51 is confined to vertical movement on the cylinder 14 by slot and stud connection therewith and carries six radially disposed arms 54. These arms are curved and extend over the pads 36 but are narrow so that they do not obstruct the operator's view of the work. Each arm 54 carries a pivoted toe post 55 and a pivoted heel post 56. These are arranged to bear upon the forepart of the lasted shoe 60 and the cone of its last and support the work against the thrust of the inflated pad.

In the normal operation of the machine the operator stands at its left hand side as shown in Fig. 1. The pad opposite to him will have been deflated by depression of the arm 41 which has moved the valve 40 to its outer position and opened the exhaust port 49. The operator is therefore free to present to the machine a lasted shoe having its outsole spotted in proper position in the shoe bottom. The deflated pad provides sufficient clearance for insertion of the lasted shoe beneath the toe and heel posts as indicated at the left in Fig. 6, and if adjustment is necessary this is conveniently effected by manipulation of the adjusting screw 35.

Having properly positioned the shoe, the operator first depresses the foot treadle 46 to inflate the pad, whereupon the pad is at once inflated and the shoe bottom subjected to the full fluid pressure of the system. He then depresses the starting handle 29 whereupon the turret is indexed 60° in a counterclockwise direction. The operator now proceeds to load each pressure unit as it comes to him with a lasted shoe and sole, and in each case the work is held under fluid pressure during the full revolution of the turret. At the conclusion of each full revolution the pad arriving before the operator has been automatically deflated by action of the deflating cam 43.

The valve controlling sleeve 40 uncovers the exhaust port 49 when the valve is moved to its deflating position as shown in Fig. 8. After the cam roll 42 leaves the deflating cam 43, the valve sleeve may be moved to inflating position in which the exhaust port 49 is closed. While the pad ordinarily remains inflated with the shoe under pressure during a turret rotation of approximately 320°, any selected pad may be deflated at any of the five intermediate stations by depressing the cam arm 41 as an emergency operation.

It will be apparent that the angle of the jacks is such that a single vertical adjustment of the head 52 will automatically position the toe posts at each pressure unit for an entire range of shoe sizes. In changing the machine to handle shoes of any given size, it is necessary for the operator to adjust properly for a single shoe at the initial station, and by so doing he has taken care of all six pressure units.

Having thus disclosed my invention and described in detail an illustrative embodiment thereof, I claim as new and desire to secure by Letters Patent:

1. A sole press of the turret type comprising a frame, a rotary carrier mounted on said frame

and projecting thereabove, a plurality of radially disposed pressure units carried by said carrier for rotation therewith and each including a downwardly and outwardly inclined inflatable pad and an overhanging arm carrying heel and toe posts, adjusting means associated with said rotary carrier for simultaneously moving all of said overhanging arms in a vertical direction relative to said pads, and a fluid pressure system having connections with said pads.

2. A sole press of the turret type comprising a frame, an upright fluid pressure cylinder mounted therein for rotary movement about a vertical axis, a series of radial arms projecting from said cylinder, a downwardly and outwardly inclined inflatable pad mounted at the outer end of each arm, a sleeve slidably supported on the upper end of said cylinder and having a radial arm corresponding to each of said pads, heel and toe posts pivoted upon the outer portion of each of said latter arms, means holding said sleeve in different adjusted positions on the upright cylinder, and a fluid pressure connection from each pad to said pressure cylinder.

3. A sole press comprising a rotary cylinder serving as a fluid pressure reservoir and also as a rotatable carrier, a series of radially disposed arms projecting from the cylinder and outwardly inclined plates fast to the arms, inflatable pads adjustably mounted on the respective plates for movement toward or from the axis of the rotary carrier cylinder, pressure connections including a valve between said cylinder and each pad with a flexible connection portion extending from each valve to each pad, a valve operating arm mounted for movement with each pad, treadle operated means for opening the valve at a predetermined position in the rotary movement of each pad, and cam operated means releasing the valve in another position of the pad.

4. A sole press of the turret type comprising a frame, a carrier mounted therein for rotation about a vertical axis, a plurality of radially disposed inflatable pads mounted thereon, a cap movably mounted on the carrier, a plurality of radially disposed work-engaging members mounted on the cap, one above each of said pads, and means for vertically adjusting the cap together with all of its said work-engaging members.

5. A sole press of the turret type comprising a frame, an upright cylinder mounted therein for rotary movement about a vertical axis, a series of radial arms projecting from said cylinder, an inflatable pad mounted at the outer end of each arm at an angle of approximately 45° to the horizontal, a sleeve slidably supported on the upper end of said cylinder and having a radial arm corresponding to each of said pads, heel and toe posts pivoted upon the outer portion of each of said latter arms, and means holding said sleeve in different adjusted positions on the upright cylinder.

6. A sole press of the character described in claim 5 in which each pad is provided with individual adjusting means for locating it beneath corresponding heel and toe posts.

7. A sole press comprising a frame, an upright cylinder mounted therein for rotary movement and containing a pressure chamber, means sealing the upper end of the chamber, inflatable pads having individual pressure connections with said

cylinder, a sleeve telescopically mounted on the upper end of said cylinder and having radial arms, adjusting means for the sleeve, and cooperating toe and heel posts carried by the radial arms.

5 8. A sole press comprising a frame having a circular top, an upright cylinder mounted in the top for rotary movement and providing a fluid pressure chamber extending at its lower end 10 within the frame of the press, a fluid pressure inlet connection to the lower end of the upright cylinder located in its axis of rotation, a sleeve telescopically mounted on the upper part of the cylinder outside the frame of the press, radially disposed work pressing units carried by the upright cylinder including in each an inflatable pad, fluid pressure connections between the inflatable pads and said pressure chamber including a radial pipe located between each pair of pressing units, a valve for opening and closing each of said connections, and a controlling arm for each valve extending within reach of the operator of the press.

25 9. A sole press comprising a frame, a rotary carrier having a plurality of radially disposed pressure units each including an inflatable pad disposed at an angle of approximately 45° to the horizontal and an overhanging arm carrying heel and toe posts, means for simultaneously adjusting all of said overhanging arms in a vertical direction thereby effecting a corresponding adjustment in each of the said pressure units, and a fluid pressure system having connections with said pads.

30 35 10. A sole press comprising a frame having a flat circular top, a rotary cylinder projecting above the top of the frame and containing a fluid pressure chamber, arms projecting radially from the cylinder and downwardly and outwardly 40 inclined pad boxes carried by said arms, fluid pressure connections between each pad box and said pressure chamber, a sleeve telescopically mounted on the upper end of the cylinder, means for adjusting the sleeve vertically upon the cylinder, and radially disposed shoe-engaging devices carried by the sleeve and simultaneously adjustable therewith.

45 50 55 11. A sole press comprising a stationary frame, a rotary cylinder projecting above the frame and containing a fluid pressure chamber of substantial volume, a series of downwardly and outwardly inclined pad boxes radially disposed in proximity to the cylinder and supported thereon, direct fluid connections between the pressure chamber and each pad box, a sleeve telescopically mounted on the upper end of the cylinder, and radially disposed shoe-engaging devices carried by the sleeve and disposed above the pad boxes.
